UNITED STATES PATENT OFFICE.

BRYCE B. PERROW, OF TACOMA, WASHINGTON.

DISPLAY-BOX.

1,399,273.

Specification of Letters Patent.

Patented Dec. 6, 1921.

Application filed December 13, 1920. Serial No. 430,401.

To all whom it may concern:

Be it known that I, BRYCE B. PERROW, citizen of the United States, residing at Tacoma, in the county of Pierce and State of Washington, have invented certain new and useful Improvements in Display-Boxes; and I do hereby declare the following to be a full, clear, and exact description of the invention, such as will enable others skilled 5 in the art to which it appertains to make and use the same.

This invention relates to new and useful improvements in display cases and more particularly to a sectional box or display 15 case which can be used either for display purposes, the main object of the invention being the provision of a case having a plurality of cells arranged within the main case whereby to contain various types of articles 20 so that the same can be readily placed on display and also to provide a removable cover for the goods whereby the whole device can be used for transportation purposes if so desired.

25 Another object of the invention is the provision of a display case wherein a number of cells are collectively arranged within a main case and suitably secured together and also secured to the main case whereby the 30 cells will be retained in their respective positions within the main case and the provision of a removable cover which can be readily removed and engaged over the bottom of the box when the articles contained 35 within the cells are on display, said cover being adapted to inclose the upper portion of the box when the case is used in transportation.

With the above and other objects in view 40 the invention consists in the novel features of construction, combination and arrangement of parts hereinafter more fully set forth, pointed out in the claim and shown in the accompanying drawings wherein;

45 Figure 1 is a perspective view of a display case constructed in accordance with my invention;

Fig. 2 is a detail longitudinal sectional view taken through one corner of the case; 50 and,

Fig. 3 is a detail section taken on the line 3-3 of Fig. 2.

Referring now more particularly to the drawings it will be noted that in the construction of my improved case I provide a

main casing 1 which may be formed of wood, metal or any other desirable material and arranged within this main case are a plurality of boxes or individual cells as indicated at 2, the box or cells in the present 60 instance being shown as arranged transversely of the case 1, the said cells being the length of the width of the box 1, but it will be understood that any number of cells may be arranged in the box and any particular 65 arrangement can be carried out and also various sizes can be used in place of the ones disclosed in the drawings.

In order to retain the cells 2 in position within the main case 1 leather binding strips 70 3 are provided, said binding strips being arranged over the adjoining edges of the cells 2 to connect the cells together and in order to retain the cells within the case 1, this binding can be arranged along the end walls 75 of each of the cells and extended over onto the top edge of the case 1 so that the cells will be readily attached to the main case. Each of the cells arranged at the ends of the case 1 are provided with a binding strip 3' 80 which extends along the entire length of the cell and having its edge engaged with the top of the end of the case and from this it will be apparent that the cells 2 will be readily secured in position within the case 85 1. The binding strip 3 is preferably of what is known upon the market as leatherette paper and is to be of sufficient width so that the same will extend across the top of the adjoining walls of the cells 2 and down 90 upon the side walls a sufficient distance to securely hold the two side walls in their adjoining position.

When the case is used for display purposes as shown in Fig. 1, the cover 1 is generally 95 indicated by the numeral 4 and is arranged over the bottom of the box so as to be entirely out of the way and readily accessible when it is desired to close the case. In Fig. 2 a portion of the cover 4 is shown arranged over the top of the box and it is preferred 100 to have this cover made of the same material as the case, although it will be understood that any suitable material may be used. One of the main advantages of this display box 105 is that fishing tackle and other similar small articles can be readily packed in the box by the manufacturer or wholesale dealer and the goods shipped to the retailer where the box can be used for display purposes. Thus 110

it will be seen that the box is not only useful as a display case, but equally as useful when shipping the goods from the manufacturer or wholesaler.

5 While I have shown and described the cells 2 as secured to the main box 1 by having the binding strip 3' extending onto the upper edges of the walls of the box, it will be understood that this can be eliminated 10 and the cells removed from the box 1 as a unit if it should be found desirable, thus it will be noted that one case or box can be used for different sized cells. For instance, 15 in Fig. 1 the cells illustrated extend from side wall to side wall of the box, but should it be desired to display a plurality of small articles requiring a great many more cells than are herein illustrated, the cells shown in Fig. 1 could be collectively removed from

the box 1 and another series of cells readily 20 inserted.

What is claimed is:

A device of the class described including a main receptacle, a removable cover therefor, said cover being engaged over the bottom of the receptacle when the receptacle is in use, a plurality of individual receptacles arranged transversely within the main receptacle and disposed in parallel relation with respect to each other providing a continuous receptacle from one side wall of the main receptacle to the other, means for connecting the abutting side walls of the individual receptacles and means for connecting the individual receptacles to the side and end 35 walls of the main receptacle.

In testimony whereof I affix my signature.
BRYCE B. PERROW.
